CIGARETTE AND CIGAR RECEIVER

Karmen D. Albert, Woodside, N. Y.

Application May 17, 1939, Serial No. 274,078

7 Claims. (Cl. 131—242)

My invention relates to improvements in cigarette and cigar receivers.

Lighted cigarettes and cigars are an ever recurring source of trouble and danger in the household, office, factory, store, or for that matter, everywhere, and ash trays and receivers in use today have not been efficacious in remedying the situation. The cigars and cigarettes roll off, the ashes drop on rugs, and perusal of the records of the insurance companies and our daily newspapers are verification of the fact that acute fire hazards exist.

This hazard is chiefly due to the fact that smokers often leave their cigars and cigarettes on the trays with the unconsumed portion extending over the side, and then neglect them, with the result that when the article is further consumed by the incandescent ash, the cigar or cigarette drops over the side of the receiver.

Further, when a cigarette is placed upon the conventional tray or receiver, the smoke from the burning ash smudges the paper contiguous to the ash, spoiling the flavor of the cigarette when it is later smoked.

I have provided a receiver which overcomes the disadvantages of the conventional tray, one object of my invention being to eliminate the danger of rolling cigarettes or cigars, and another, to prevent the smoking or smudging of the paper contiguous to the burning ash of the cigarette.

Generally, my invention comprises a receptacle and a member which is hereinafter styled a grating, the grating consisting of plates with intermediate bars from which extend closely spaced prongs or nubs, the distance therebetween being such that a cigarette or cigar will always rest upon the ends of the prongs when placed thereupon, no matter where positioned.

Additionally, the grating may be easily turned over to dump any ashes or extinguished cigars or cigarettes into the receptacle portion of the receiver.

The stated objects and others, as well as the means of their attainment will be apparent after a perusal of the following specification, taken in conjunction with the drawing.

In the drawing,

Fig. 1 is a perspective view of the invention 50 with a portion of the receptacle broken away.

Fig. 2 is a cross section of the grating and receptacle taken along lines 2—2.

Fig. 3 illustrates a side elevation of one of the rows of prongs and mountings.

Fig. 4 depicts a modified prong showing the ends rounded.

Fig. 5 is a section taken along lines 5—5 of Fig. 3.

5 In the drawing, referring particularly to Fig. 1, 6 depicts the receptacle portion 6 of the receiver, which in the form shown is a rectangular parallelepiped, with base 7, sides 8, ends 9 and an open top. Medially of the top of ends 9 are formed notches 10, having flat bottoms.

While I have indicated the receptacle portion of the receiver in the shape of a rectangular parallelepiped, this portion may be in any other desired form, dish-shaped, or otherwise.

15 Fitting in the open top of the receptacle there is a grating 11, of novel structure, consisting of a plurality of longitudinally disposed bars 12, from which equidistantly extend prongs 13, one set above and one below. While I have shown prongs 13 in this relationship, I may employ but one set of prongs, that is, extending above bars 12, and further, the bars may be disposed other than longitudinally.

In Fig. 1, I have illustrated prongs having flat 25 extremities, while Figs. 3 and 4 depict a modified form, wherein the extremities are rounded. Any shaped prong may be employed, as long as the extremity is not so pointed as to injure the fingers of one using the receiver.

I prefer to have the extremities of members 13 slightly below the upper edge of receptacle 6 when the grating is set as indicated in Figs. 1 and 3, so that if a cigarette or cigar is placed near the edge of 6, it will not roll from the receiver.

35 The distance between bars 12, and that between prongs 13 extending therefrom is such that a cigarette will rest at any point upon the extremities of one set of prongs without falling into receptacle 6.

40 In the embodiment shown, a die may be used to strike out each row of equidistantly extending prongs from a single sheet of metal. However, any other suitable material, or method of manufacture, i. e., casting, can be employed to achieve equivalent results.

The terminals of bars 12 are riveted or otherwise fixedly secured to end plates 14, see Figs. 1, 3 and 4, with the portion adjacent plates 14 being slightly larger than the prongs to assure a firm connection.

Both plates 14 are provided with shafts having outer heads 15 and inner heads 16, with the intermediate portions 17 flat on opposite sides. 55 Stub shafts 18 are turned over or swaged on the

inner side of end plates 14, while on outer heads 15 are mounted thumb wheels 19.

Referring to Figs. 1 and 5, it will be noted that the sides of intermediate portion 17 lie flat in the bottom of notches 10, when grating 11 is positioned for receiving cigarettes or cigars, so that the grating will not rotate when in use, as in Fig. 1.

I have determined that when a lighted cigarette is placed upon the grating, and allowed 10 to remain there for any length of time, no smoking, discoloration or smudging of the paper contiguous to the burning ash results, as it does in the trays or receivers in use today. This is due to the fact that air circulates so freely 15 around the cigarette, and around the minute extremities of prongs 13 upon which the cigarette is resting, that it is evenly consumed. Furthermore, the cigarette may be extinguished, if desired, by rubbing the burning end across one or more of the exposed prongs 13.

In trays and receivers commonly employed, the surface contiguous to the reposing cigarette is very much greater, and the smudging and discoloration of the cigarette results, I believe, from the temperature of this surface being less than the temperature of the burning cigarette, with consequent collection of moisture on this surface, which is picked up by the cigarette.

After the receiver has been in use for some time, ashes may collect along the sides of prongs 13 and there will be extinguished cigarettes lying on the surface of grating 11. To dump these and free prongs 13 of ashes, grating 11 should be turned over by revolving either one or both of wheels 19. As illustrated in Fig. 2, a space is left below the plane in which grating 11 revolves and the bottom of the receptacle 6, for receiving extinguished cigarettes and ashes. Receptacle 6 may be cleaned by lifting out grating 11 and throwing away what has collected in the bottom of the receptacle.

With my invention, I have not only absolutely eliminated the smoking and smudging of cigarettes and cigars, but I have provided a receiver on which the burning article may be placed and left, with the assurance that it will not roll off—no matter how much of it may be consumed. It requires no skill to use, and may be employed anywhere with safety.

In its broader aspects the invention comprehends the employment not only of the means described, but of equivalent means for performing the recited functions. It is desired to reserve the right to effect such changes as may come fairly within the scope of the appended claims.

I claim:

1. A device of the character described, including a receptacle, a rotatable grating mounted in the receptacle, and comprising a pair of end plates and intermediate bars connecting the plates, each of said bars having oppositely disposed prongs extending therefrom adapted to receive a cigarette or cigar.

2. A device of the character described, including a receptacle, a rotatable grating mounted in the receptacle, and comprising a pair of end plates and intermediate bars connecting the plates, and closely spaced, oppositely disposed prongs extending from each of said bars, the terminals of said prongs adapted to receive a cigarette or cigar.

3. A device of the character described, comprising a receptacle with notched ends, a rotatable grating having end-plates and intermediate bars connecting the plates, each of said bars provided with closely spaced, oppositely disposed prongs, said end-plates carrying shafts, and a manipulating wheel mounted on one of said shafts for rotating the grating.

4. A device of the character described, comprising a receptacle with ends having notches with straight lower edges, a grating consisting of end plates and intermediate bars connecting the plates, each of said bars having closely spaced prongs and each of said plates provided with a shaft, the intermediate portions of which have opposite flat sides designed to rest upon the aforementioned edges of the notches.

5. A device of the character described, including a receptacle, a rotatable grating mounted in said receptacle and comprising a pair of end plates and intermediate bars connecting the plates, each of said bars having closely spaced, oppositely disposed prongs, the terminals of which are below the plane of the upper edge of said receptacle.

6. A device of the character described, including a receptacle, a grating mounted in said receptacle and comprising a pair of end plates and intermediate bars connecting the plates, each of said bars having closely spaced, oppositely disposed prongs, the terminals of which are below the plane of the upper edge of said receptacle.

7. A device of the character described, comprising, in combination, a receptacle, and a grating having a plurality of closely spaced, oppositely disposed, vertical projections extending throughout the length and breadth of the upper and lower faces of said grating adapted to support a cigarette or cigar in a plane at substantially right angles to said projections.
